(57) **CLAIM**

The ornamental design for a rear light for bicycle, as shown and described.

DESCRIPTION

FIG. 1 is a front-right-top perspective view of the rear light for bicycle showing my new design;

FIG. 2 is a front elevational view thereof;

FIG. 3 is a rear front elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view from another angle of view thereof; and,

FIG. 9 is a perspective view from the other angle of view thereof.
